UNITED STATES PATENT OFFICE

2,419,605

THREAD-ADVANCING REEL

Richard W. Stanley, Drexel Hill, Pa., assignor to
American Viscose Corporation, Wilmington,
Del., a corporation of Delaware

Application May 19, 1945, Serial No. 594,730

13 Claims. (Cl. 28—71.6)

1

The present invention relates to an improved thread-advancing reel and is chiefly concerned with improvements for increasing the mechanical efficiency of the reels so that they may handle heavier and stronger yarns, whether they be of artificial or natural filamentary material, or even large yarns or tows obtained from artificial filament spinning machines. The invention is also concerned with an improved form of internal sealing structure to protect the bearings and moving parts of the reel from corrosive action of any liquids that may be played upon the threads carried by the reels.

In thread-advancing reels containing two sets of bars, either of the type where both sets are concentric or of the type in which one set of bars is eccentric to the other and in which the thread-advancing action is accomplished by reciprocation of some or all of the bars either individually or as groups, it is desirable to reduce to a minimum the frictional forces required to be overcome in effecting such reciprocation of the bars. In accordance with the present invention, roller bearings are provided for carrying the bars in order to reduce the mechanical effort required to effect reciprocation of the bars. To further increase the efficiency of the rollers, means are provided for assuring that the rollers cannot lag or become caught adjacent one end of their rollway. This auxiliary means is desirable and important since the rollers do not always return to their initial position during the return stroke of the bar because of the fact that during the return stroke of the bar, the thread load is removed therefrom and in addition centrifugal force acts upon the bar, especially at high rotative speeds, and tends to lift or reduce the pressure of the bar upon the rollers. The result is that the bar itself sometimes does not exert sufficient pressure upon the rollers during its return stroke to return the rollers to starting position, and upon the next thread-advancing stroke when the bar is carrying the thread and is under load, the rollers may be at the end of their movement, so that the bar must slide with respect thereto instead of having rolling contact. Other influences which may tend to cause lagging or improper placement of the rollers at the beginning of the thread-advancing stroke even when full pressure of the bar and its load bears on the roller, include the use of heavy grease as lubrication and the possibility that such grease may be hardened or dust or abraded particles may accumulate and cause sticking or jamming of the rollers. These influences may also tend to cause

2

relative sliding action of the bars with respect to the rollers even during the thread-advancing stroke. Therefore, the present invention preferably provides the auxiliary means projecting into the path of the rollers for preventing lagging thereof and for assuring their return at least a minimum predetermined distance after each load-carrying movement and in case of necessity for assuring their movement during the thread-advancing stroke. An ancillary object of the present invention is to provide an improved sealing arrangement arranged to protect the roller bearings as well as the other bearing structures and driving mechanism within the heart of the reel as a whole. These objects as well as others and additional advantages will be apparent from the drawing and the description thereof hereinafter; in which—

Figure 1 is a side elevation with the upper half 20 in cross section, of one embodiment of the reel;

Figure 2 is a cross section taken on line II—II of Figure 1;

Figure 3 is a cross section taken on line III—III of Figure 2;

Figure 4 is a perspective of a detail;

Figure 5 is a perspective of another detail;

Figure 6 is a section of a modification taken on a line corresponding to that on which Figure 2 was taken in the reel of Figures 1 to 5;

Figure 7 is a section on line VII—VII of Figure 6; and

Figure 8 is a perspective of a detail.

As shown in Figures 1 to 5, the reel is of that type which comprises one set of bars fixed for rotation about an axis and a second set of actuatable bars interdigitating between the fixed bars and mounted for rotation upon an axis eccentric with respect to the axis of the fixed set of bars. It should be understood, however, that 40 it is merely illustrative and that the bearing construction can be applied as well to bars of the type of reel in which there are two actuatable concentric sets of bars.

In the specific construction shown, a supporting frame 2 and the bracket 3 extending therefrom serve to support the reel rotatably upon a shaft 4 which may be hollow as shown. The concentric set of reel bars 5 is secured between solid plates or flanges 6 and 7 of suitable structure, bolts 8 serving to tie the flanges and bars together as a cage-like unit. The flange 6 has a recess 9 in its outer face, so that a doffing ring or sleeve 10 which is keyed to the stationary shaft 4 at 11 may extend under the shoulder thereby left upon the flange. Flange 7 may be provided

with coupling projections 12 adapted to fit within mating recesses in the coupling 13 mounted rotatably within the frame 2 and adapted to be driven by the spline shaft 14 secured to the shaft 15.

The actuatable bars 16 are each attached individually to rods 17 by screws 18 and braces 19. An annular reinforcing ring 19' is secured internally of the cage of bars 5 by screws 18', and extends through the space between bars 16, rods 17 and the interconnecting braces 19 without impeding the movement of these parts during thread-advancing action. Each end of the rods 17 co-operates with roller bearings 20 arranged to roll back and forth in the direction of the axis of the reel across the width of the annular rings 21 which are supported by composite webs 22 rotatably mounted on bearings 23 upon eccentric bushings 24 fixedly secured to the stationary shaft 4. Skew plates 25 are rotatably mounted by bearings 26 upon bushings 27 whose bearing surfaces are both eccentric and askew with respect to the axis of shaft 4. It will be noted that the annular rims of the plates 25 are in engagement with projections from the rods 17 so that during rotation of the reel the askewness of the plates 25 causes reciprocating movement of the rods 17 with bars 16 longitudinally.

As shown to better effect in Figures 2 and 3, the end of each rod 17 is provided with a fixed collar 28 from which a portion of the rod extending from the collar has a flattened cross section as shown at 17' in Figure 2. Upon the flattened end of the rod a bearing block 29 is positioned between two spacing sleeves 30 and two washers 31 provided with projecting lugs 32, the entire assemblage being held securely in place by the nut 33 engaging a threaded end portion of the rod. The sleeves 30 fit freely for relative movement within apertures formed in the side walls 22a and 22b of the bearing housing formed by stamping an annular recess in each of the two plates forming the web 22. Additional apertures 34 are provided in the walls 22a and 22b so that the lugs 32 may enter more or less in alignment with the path of the rollers 20. The general shape of the washers 31 and the general shape of the washers 31 and the shape of the bearing block 29 are shown in Figures 4 and 5.

For sealing the internal bearing and driving parts a rigid cylindrical sleeve of an impermeable corrosion resistant material is clamped between the end webs 22 and flexible sealing membranes 36 of generally annular shape have their inner periphery clamped in place between the edges of the sleeve 35 and webs 22 and their outer peripheries clamped in place between the bars 5 and the flanges 6 and 7, spacing members 37 being provided to assure a tight gripping action. The flexible annuli 36 may be of rubber, synthetic rubber or any rubber substitute of impermeable corrosion-resistant character and are provided with apertures through which the rods 17 may extend. The edge of such apertures may be held tightly in place between the collars 28 and the adjacent washers 31, the outer edge of the collars 28 being bulged to assure a tight sealing action.

During operation of the embodiment of Figures 1 to 5, the cage-like assembly of bars rotates as a unit about the stationary shaft 4, the skew plates 25 causing reciprocation of the rods 17. The lugs 32 which are moved simultaneously with the rods 17 are caused to project into the path of the rollers 20 and serve to prevent such rollers

either to lag or to become stuck in any position adjacent the end of its path of movement.

Figure 3 shows the bearing at a point intermediate the stroke of the bar or rod 17. Since the center of the roller moves only half the distance moved by the rod in a stroke, it is only necessary that a given projection 32 on the washer 31 project into the bearing housing, at the end of the stroke, a distance equal to one-half the stroke of the rod. Thus, at the end of the stroke to the right, the lugs 32 at the left in Figure 3 should extend into the housing and beyond the wall 22a a distance at least one-half the length of the stroke and conversely upon completion of the stroke to the left, the lug 32 at the right should extend a distance within the wall 22b at least one-half the length of the stroke.

Figures 6 to 8 illustrate a modification in which the bearing means for each end of each rod supporting an actuatable bar comprises an additional roller 40 which rides within a slot 41 in the bearing block 29a, aligned slots being provided in the adjacent sleeves 30a. The roller 40 bears against the upper flat surface of the rod 17a' and rides upon and within an outer ring 21' within the bearing housing formed in the outer portion of the web 22' which, as in the embodiment of Figures 1 to 5, is of composite character and may comprise two stamped plates. In this embodiment, additional projections 32a are provided upon the washers 31a. Openings are provided in the walls of the housing to allow the projections 32a to extend into the path of the roller 40 and to serve with respect to roller 40 in an analogous manner to the projections 32 with respect to roller 20. It will be seen that this construction provides for a roller bearing upon the return stroke even when the bar is thrown outwardly by centrifugal force so that it would not be carried by rollers 40 during such return stroke. Whereas in the embodiment of Figures 1 to 5, the movement of the rod 17 during the return stroke may involve a certain amount of friction of the bearing block 29 against the ceiling within its housing on webs 22 (or perhaps of the sleeves 30 within the apertures in walls 22a and 22b depending upon the precise construction), in the embodiment of Figures 6 and 8, the bars ride back on rollers 40 with a minimum of friction.

The bars 16 in either embodiment may be actuatable individually or a plurality of adjacent bars may be interconnected for simultaneous movement. Thus, adjacent bars 16 may be paired off so that two of them are connected to a common rod 17 through braces 19 which may then be U-shaped when viewed in the direction corresponding to that from which Figure 2 is taken. In this manner, the number of rods 17, rollers 20, and associated parts 29, 30, 31 and the like may be greatly reduced.

The invention thus provides a more efficient construction capable of handling heavy yarns and tows and is also especially applicable to long 65 rods having heavy bars needed to support long helices while being subjected to a plurality of liquid treatments in succession. In long reel constructions, it may be desirable to provide a plurality of roll and end roller bearing supports spaced longitudinally of each actuatable bar to provide the additional strength necessary.

It is to be understood that changes and variations may be made without departing from the spirit and scope of the invention as defined in 70 the appended claims.

I claim:

1. A thread-advancing reel comprising a rotatably mounted supporting means, bearing means carried on the supporting means and comprising rollers rotatable on axes directed transversely to the axis of rotation of the supporting means and a plurality of bars reciprocably carried by the rollers.

2. A thread-advancing reel comprising a rotatably mounted supporting means, bearing means carried on the supporting means and comprising rollers rotatable on axes directed transversely to the axis of rotation of the supporting means, a plurality of bars reciprocably carried by the rollers, and means projecting into the path of the rollers for preventing lagging thereof and for assuring their return at least a minimum predetermined distance after each reciprocation.

3. A thread-advancing reel comprising a plurality of bars, roller bearing means for supporting the bars, means for reciprocating the bars, and means associated with the rollers for preventing lagging thereof and for assuring their return at least a minimum predetermined distance after each reciprocation.

4. A thread-advancing reel comprising a plurality of bars, roller bearing means for supporting the bars, means for reciprocating the bars, and means projecting into the path of the rollers for preventing lagging thereof and for assuring their return at least a minimum predetermined distance after each reciprocation.

5. In a thread-advancing reel, a reel bar supporting structure comprising a rotatable support, roller means movably carried by the support, means for constraining the rolling movement of the roller means to a direction transverse of the plane of rotation of the support, and a longitudinally reciprocable bar carried by the roller means so that the bar rides in rolling contact with the roller means.

6. In a thread-advancing reel, a reel bar supporting structure comprising a rotatable support, roller means movably carried by the support, means for constraining the rolling movement of the roller means to a direction transverse of the plane of rotation of the support, a longitudinally reciprocable bar carried by the roller means so that the bar rides in rolling contact with the roller means, and means projecting into the path of the rollers for preventing lagging thereof and for assuring their return at least a minimum predetermined distance after each reciprocation.

7. In a thread-advancing reel, a reel bar supporting structure comprising a rotatable support, longitudinally reciprocable thread-carrying bar, at least one roller carried on the support and arranged for rolling movement generally axially of the reel, and bearing means for the bar comprising a bearing surface adjacent one end thereof of making rolling contact with the roller.

8. In a thread-advancing reel, a reel bar supporting structure comprising a rotatable support, a longitudinally reciprocable thread-carrying bar, at least one roller carried on the support and arranged for rolling movement generally axially of the reel, bearing means for the bar comprising a bearing surface adjacent one end thereof of making rolling contact with the roller, and means projecting into the path of the rollers for preventing lagging thereof and for assuring their return at least a minimum predetermined distance after each reciprocation.

9. In a thread-advancing reel, a reel bar supporting structure comprising two supports rotatable about a common axis and spaced apart axially, at least one roller carried on each support and arranged for rolling movement generally axially of the reel, a longitudinally reciprocable thread-carrying bar, and bearing means for the bar comprising a bearing surface adjacent each end thereof of making rolling contact with the corresponding roller.

10. In a thread-advancing reel, a reel bar supporting structure comprising two supports rotatable about a common axis and spaced apart axially, at least one roller carried on each support and arranged for rolling movement generally axially of the reel, a longitudinally reciprocable thread-carrying bar, bearing means for the bar comprising a bearing surface adjacent each end thereof of making rolling contact with the corresponding roller and a pair of members fixedly connected to the bar on opposite sides of the bearing surface adjacent each end thereof and arranged to project into the path of the corresponding roller for preventing lagging thereof and for assuring its return at least a minimum predetermined distance after each reciprocation.

11. In a thread-advancing reel, a reel bar supporting structure comprising two supports rotatable about a common axis and spaced apart axially, each of the supports comprising a radially outwardly facing bearing surface and a radially inwardly facing bearing surface, a longitudinally reciprocable thread-carrying bar, bearing means adjacent each end of the bar comprising a radially inwardly facing and a radially outwardly facing bearing surface each facing opposite one of the bearing surfaces on the corresponding support, and a roller arranged between each pair of opposed bearing surfaces for rolling movement generally axially of the reel.

12. In a thread-advancing reel, a reel bar supporting structure comprising two supports rotatable about a common axis and spaced apart axially, each of the supports comprising a radially outwardly facing bearing surface and a radially inwardly facing bearing surface, a longitudinally reciprocable thread-carrying bar, bearing means adjacent each end of the bar comprising a radially inwardly facing and a radially outwardly facing bearing surface each facing opposite one of the bearing surfaces on the corresponding support, and a roller arranged between each pair of opposed bearing surfaces for rolling movement generally axially of the reel and members fixedly connected to the bar on opposite sides of the bearing surfaces adjacent each end thereof and arranged to project into the paths of the corresponding rollers for preventing lagging thereof and for assuring their return at least a minimum predetermined distance after each reciprocation.

13. A thread-advancing reel comprising supporting means rotatable about an axis and having two axially spaced generally annular housings, an annular bearing in each housing, a plurality of reciprocable thread-carrying bars, bearing means for the bars projecting through the housings and being relatively movable axially with respect thereto, rollers arranged between and in rolling contact with the annular bearing and the bar bearing means for rolling movement generally axially of the reel, and means for reciprocating the bars.

RICHARD W. STANLEY.
